(57) **CLAIM**

The ornamental design for a ledged takedown lever for a pistol, as shown and described.

DESCRIPTION

FIG. 1 is a top, front, left-side perspective view of a ledged takedown lever for a pistol showing my new design;

FIG. 2 is a top, front, right-side perspective view of the ledged takedown lever for a pistol;

FIG. 3 is a top, rear, left-side perspective view of the ledged takedown lever for a pistol;

FIG. 4 is a top, rear, right-side perspective view of the ledged takedown lever for a pistol;

FIG. 5 is a bottom, front, left-side perspective view of the ledged takedown lever for a pistol;

FIG. 6 is a bottom, front, right-side perspective view of the ledged takedown lever for a pistol;

FIG. 7 is a bottom, rear, left-side perspective view of the ledged takedown lever for a pistol;

FIG. 8 is a bottom, rear, right-side perspective view of the ledged takedown lever for a pistol;

FIG. 9 is a top plan view of the ledged takedown lever for a pistol;

FIG. 10 is a bottom plan view of the ledged takedown lever for a pistol;

FIG. 11 is an enlarged front elevational view of the ledged takedown lever for a pistol;

FIG. 12 is an enlarged rear elevational view of the ledged takedown lever for a pistol;

FIG. 13 is a right-side elevational view of the ledged takedown lever for a pistol;

FIG. 14 is a left-side elevational view of the ledged takedown lever for a pistol; and,

FIG. 15 is a top, front, right-side perspective view of a ledged takedown lever for a pistol in a use configuration with a pistol.

The broken lines in FIG. 15 depict the environment of a pistol that forms no part of the claimed design.
